UNITED STATES PATENT OFFICE.

ROBERT A. MOORE, OF CHICAGO, ILLINOIS.

TRIGGER-CONTROLLER.

953,279.

Specification of Letters Patent. Patented Mar. 29, 1910.

Application filed February 2, 1910. Serial No. 541,555.

To all whom it may concern:

Be it known that I, ROBERT A. MOORE, a citizen of the United States, residing at Chicago, in the county of Cook and State of Illinois, have invented certain new and useful Improvements in Trigger-Controllers, of which the following is a specification.

This invention relates to fire arms adapted especially for military purposes and consists 10 in certain specific novel features of improvement over the device patented to me on January 11, 1910, No. 945,852. As in the previous construction this device is designed for the purpose of preventing the pulling of the 15 usual trigger when the fire arm is held at any elevation or inclination above or below the inclination at which it is intended that it should be fired.

When arms are equipped in the manner 20 herein suggested the commanding officer or other qualified person will indicate to the person or persons manipulating the fire arms the degree of elevation at which the firing is to be done, and by means of any suitable adjusting and indicating devices carried by the 25 fire arm and associated with the trigger controller *per se* the latter device will be ready for use in accordance with instructions given.

30 For a full understanding of the present improvement reference is to be had to the following detail description and the accompanying drawings, in which—

35 Figure 1 is a vertical longitudinal section, certain parts being in elevation; Fig. 2 is a vertical transverse section substantially on the broken line 2—2 of Fig. 1, and Fig. 3 is a side elevation of the casing and indicating devices associated therewith.

40 Throughout the following description and on the several figures of the drawings similar parts are referred to by like reference characters.

45 At 10 is indicated a conventional form of trigger plate from which extends downwardly a trigger guard 11, and 12 indicates the usual trigger. Mounted upon the trigger plate and secured thereto in any suitable manner is a casing 13. Mounted transversely within the casing is a shaft 14 upon which is suspended a pendulum 15, freely movable on the shaft within certain limits defined by devices hereinafter described.

50 Any suitable means may be employed for adjusting the shaft rotatably in the casing. The means shown for this purpose includes

a gear 16 secured upon one end of the shaft 14, an indicator wheel 17, adapted to be operated by a thumb or finger of the operator, and intermediate gears between the indicator wheel and the aforesaid gear 16, whereby the shaft 14 may be rotated and adjusted very delicately. It is to be understood that the shaft 14, except for the adjustment just noted, may be regarded as stationary, 65 and when in use it will be held in the casing in a rigid or stationary position.

At 18 is indicated any suitable form of plunger slidable vertically and transversely through the shaft 14. The position of the 70 plunger with respect to rotation around the axis of the shaft 14 will of course be determined by the position of the shaft, so that during ordinary usage the plunger is non-rotary. The plunger at its lower end 75 co-operates with the lower portion of the pendulum 15, the extreme lower end of the plunger being adapted, when the axes of the plunger and pendulum coincide, to pass into a slot or cavity 15' in the bottom of the 80 pendulum. When the axes aforesaid do not coincide the plunger is adapted to abut against one or the other of a pair of shoulders 15" on opposite sides of said slot, whereby the plunger is prevented from sliding 85 through the shaft.

Any suitable intermediate devices may be provided between the plunger and the trigger whereby the pulling of the latter may be controlled from the former. As shown 90 herein the plunger is connected at its upper end through a pair of lugs 18' through the end of a lever 19 pivoted in the casing at 20, the lugs operating in a pair of grooves 19' on opposite sides of said lever. The grooves 95 are preferably curved on arcs of circles concentric with the axis of the shaft 14, whereby the adjustment of the shaft and with it the plunger may not be interfered with by co-operation between the plunger and said lever 19. The opposite end of the lever 19 is provided with a downwardly projecting toe or cam 19". A false trigger 21 co-operates with the trigger 12 and is pivoted 100 in the casing, as at 22. The upper end of the false trigger is formed into a cam 21', which engages the aforesaid cam 19" in the rear of the latter, whereby when the triggers are pulled the cam 21' will operate 105 upon the cam 19", causing the grooved end of the lever 19 to be swung downwardly and the plunger to be moved through the shaft 110.

and into the slot in the bottom of the pendulum. When the plunger and pendulum are in interengaging position an attempt to pull the triggers will be resisted in the manner above set forth, the strain in the region of the plunger being received by the lugs 18', but by virtue of the fact that the cam end of the lever 19 is short and also in view of the peculiar form and coöperation of the cams, a large portion of such strain will be received upon the pivots 20 and 22, relieving the strain upon the lugs 18' to this extent. The movable parts will normally be held in the position indicated in Fig. 1 by 15 any suitable form of spring, indicated herein at 23, coöperating with the lever 19. The spring might be arranged in any other suitable position, and in this connection it is to be noted that I do not wish to be limited 20 to the exact form and arrangement of the parts herein illustrated.

Sometimes it is desirable to throw the controller into such a position as to enable the operator to disregard it and use the fire arm in the usual manner. Any suitable means may be resorted to for accomplishing this purpose, but as indicated the lever 19 is provided with cavities or notches 24 into which the upper end or lugs 18' of the plunger 30 may pass when the pendulum and plunger are swung around through a sufficiently large angle to bring such lugs opposite the notches. When in this position the said lugs will not prevent the downward swinging 35 movement of the lever 19 and hence the trigger may be pulled freely just as though the fire arm was not equipped with the controller.

I claim:

- 40 1. The combination with a trigger, of a controller therefor comprising a shaft, a pendulum suspended on the shaft, a plunger consisting of a unitary member slideable transversely through the shaft and adapted 45 to impinge against the pendulum under certain conditions, and devices between the trigger and the plunger to cause the latter to move independently of the pendulum under other conditions.
- 50 2. The combination with a trigger, of a controller therefor comprising a shaft, a plunger consisting of a unitary member mounted to slide transversely in said shaft, a pendulum swung upon the shaft and co- 55 operating with the lower end of the plunger,

the pendulum having a slot opposite the lower end of the plunger, and devices between the plunger and the trigger to prevent pulling of the trigger when the aforesaid slot is out of alignment with the plunger. 60

3. In combination with a trigger, a shaft, a pendulum suspended upon the shaft, a plunger slideable transversely of the shaft and coöperating at its lower end with the pendulum, and devices between the trigger 65 and the plunger to control the movement of the trigger, said devices including a grooved lever to which the upper end of the plunger is connected.

4. In combination with a trigger, a shaft, 70 a pendulum suspended upon the shaft, a plunger slideable transversely of the shaft and coöperating at its lower end with the pendulum, and devices between the trigger and the plunger to control the movement of 75 the trigger, said devices including a lever having a pair of grooves on opposite sides into which parts of the plunger extend.

5. In combination with a trigger, a shaft, means to adjust the shaft rotatably around 80 its axis, a plunger movable transversely of the shaft and adjustable therewith around the axis of the shaft, a pendulum swung upon the shaft and coöperating with the lower end of the plunger, and devices be- 85 tween the trigger and the plunger whereby the pulling of the trigger is controlled with reference to the relative positions of the pendulum and plunger, said devices includ- 90 ing a lever having a groove with which the plunger is engaged, said groove being curved on an arc whose center normally co- 95 incides with the axis of the shaft.

6. In combination with a trigger, a shaft, a pendulum suspended upon the shaft, a 95 plunger slideable transversely of the shaft and coöperating at its lower end with the pendulum, and devices between the trigger and the plunger to control the movement of the trigger, said devices including a grooved 100 lever to which the upper end of the plunger is connected, said grooved lever being notched, substantially as set forth, to permit free movement of the trigger.

In testimony whereof I affix my signature 105 in presence of two witnesses.

ROBERT A. MOORE.
